JOSEPH W. LEGG, OF WILKINSBURG, PENNSYLVANIA, ASSIGNOR TO WESTINGHOUSE ELECTRIC & MANUFACTURING COMPANY, A CORPORATION OF PENNSYLVANIA

OSCILLOGRAPH-LAMP-CONTROL MEANS

Application filed June 7, 1926. Serial No. 114,187.

My invention relates to oscillographs and particularly to means for controlling the light sources thereof.

One object of my invention is to provide means for controlling the light source of an oscillograph or similar device that shall permit of instantaneous illumination of the instrument.

Another object of my invention is to provide means for maintaining the filament of light sources for oscillographs at a desired temperature after being heated instantaneously.

A further object of my invention is to provide control means for an oscillograph that shall condition the same for instant demand during long periods of time to record conditions in a commercial transmission line when a short-circuit phenomenon occurs.

In the prior art, the light sources of electric indicating devices, such as oscillographs, are not supplied with any means for accelerating the heating thereof, an appreciable length of time being required for the accumulation of sufficient energy to cause the light source to emit an adequate intensity of light to permit the instrument to function. The time consumed for the heating of the filament is so great that if is necessary to await the energization of the light source and make photographs by use of a shutter which complicates the apparatus and operation, and renders the instrument useless for recording such momentary phenomena as a chance short circuit on commercial power lines.

In my invention, the filament of the light source is heated to a high temperature in a very brief period of time, by the discharge of an adequate quantity of stored electrical energy, as from a condenser or inductance through the said filament, and is subsequently maintained at a desired temperature by another energy supply. The time consumed to provide the illumination necessary to the operation of the instrument is so brief as to be almost negligible, and no shutter need be used to make photographs. Thus, the record may start practically instantaneously with the discharge of the stored energy into the light source.

Fig. 1 of the accompanying drawings is a diagrammatic view of an electrical installation embodying my invention in which a condenser supplies the stored electrical energy.

Fig. 2 is a diagrammatic drawing of an electrical installation embodying my invention in which a transformer supplies the stored electrical energy.

As shown in Fig. 1, the device comprises, in general, a light source 1, a control relay 2, a condenser 3, a battery 4 and a resistor 5.

The light source 1 is a lamp of a usual type found in oscillographs. It is supported by a socket 6, to the terminals of which are attached the conductors of a circuit 8, to be hereinafter described.

The control relay 2 is of a usual quick-acting type embodying a coil 20 that is energized directly from, or through a transformer 21 connected to a commercial transmission line 22 and so constructed and connected that it closes the relay on the occurrence of a short circuit in the line. The coil 20 may also be connected across an inductive shunt in a direct-current power line.

The condenser 3 is a standard condenser of sufficient capacitance to hold a quantity of electrostatic energy when charged to the potential of the battery 4, to heat the filament of the light source 1 to at least its normal brilliancy.

The battery 4 is a battery of high voltage capable of supplying sufficient energy to energize the condenser 3 to perform its function in heating the filament of the light means, and, when the control relay 2 is closed, to maintain the filament of the light source 1 at a high degree of luminosity.

The resistor 5 is of sufficient resistance to reduce the current flowing to the proper value, when the light source 1 is energized directly by the battery 4.

When the control relay 2 is open in its normal position, a circuit 7 is formed, comprising the battery 4, the resistor 5 and the condenser 3. Once the condenser 3 becomes charged to the full potential difference of the battery 4, no current flows in the circuit 7.

The light source 1 and the control relay 2

are connected in series across the condenser and form a circuit 8 in series with the battery 4 and the resistor 5. With the control relay 2 open, no current flows in circuit 8. 5 The coil of the control relay 2 is so designed that the relay closes when a short circuit occurs on the line, the phenomenon of which is to be recorded. When this phenomenon occurs, the control relay 2 is closed to permit 10 nearly all of the electrostatically stored energy of the condenser 3 to discharge through the light source 1, heating the filament thereof to at least normal brilliancy.

The closing of the control relay 2 completes 15 the circuit 8, and current from the battery 4 flows through the resistor 5 and the light source 1, which may be maintained at any desired degree of luminosity by properly selecting the resistor 5.

20 By the above described installation, a means is provided for instantaneously lighting the light source 1 and thereby causing a record to be made on the photographic film 23 in accordance with the deflections of an 25 oscillograph deflecting element 24 beginning virtually the instant the short circuit is of sufficient magnitude to close the control relay 2. The deflecting element 24 may be connected across the line 22 through a resistance 30 element 25 as shown.

The installation in Fig. 2 is an adaptation 35 of my invention, for the instantaneous heating of the filament of the light source of an oscillograph, embodying a transformer as the means of storing the electrical energy to heat the filament. It comprises, in general, a light source 1, a control relay 2, a transformer 9, a valve 10, a battery 11 and a resistor 12.

The light source 1 and the control relay 2 40 are of usual types, as hereinbefore described, except that the normal position of the control relay 2 is closed instead of open and its coil is so connected to a transmission line to be tested that it opens when a short circuit occurs 45 in the line.

The transformer 9 is of a usual type, but 50 relatively large, for reducing the alternating-current voltage applied to terminals 13 to a proper value to supply the light source 1, when photographs are being made by the oscillograph. It comprises an iron core 14, a primary coil 15 and a secondary coil 16.

There are many more turns in the primary winding 15 than in the secondary winding 16. 55 The valve 10 is a one way valve of a usual type adapted to rectify alternating current flowing through it from the terminals 13. The battery 11 is a storage battery comprising a small number of cells.

60 The resistor 12 is adjustable and of such resistance that a portion of it will restrict the current flowing in a circuit 17, to be hereinafter described; the other portion across which the valve 10 is connected, as 65 hereinafter explained, is of such resistance

that a relatively large current will cause a greater drop in potential in it than the potential drop across the valve 10, while a small current will cause a drop of potential less than that across the valve 10.

70

When the control relay 2 is closed, three circuits 17, 18 and 19 are comprised by the above described elements, a pulsating-current circuit 17, a continuous-current circuit 18, and the circuit 19 which carries current only 75 when the instrument is in operation.

The pulsating current circuit 17 extends from one of the terminals 13, through a portion of the resistor 12, which reduces the quantity of current flowing, through the one-way valve 10, the contact members of the control relay 2, the battery 11 and back to the complementary terminal 13. A relatively large quantity of current flows in circuit 17 to cause a large drop of potential in the resistor 12, the valve 10 being connected across a sufficiently long portion of the resistor 12 to provide an easier path for the large current, with the result that virtually all the current flows through the valve 10 and is rectified to pass through the battery 11 and maintain it in charged condition.

80

The continuous-current circuit 18 extends from one terminal of the battery 11 through the primary coil 15 of the transformer 9 and across the contact members of the control relay 2 to the complementary terminal of the battery 11. The continuous current maintains a strong electromagnetic field in the core 14 of transformer 9.

85

The circuit 19 comprises the secondary winding 16 of the transformer 9 and the light source 1.

90

When the control relay 2 is opened by a short circuit in the line to which it responds, the circuit 18, which carries the current maintaining the electromagnetic field in core 14 of transformer 16, is opened, and the stored electric energy in the core 14 discharges itself 100 instantaneously, through the secondary coil 110 16, thereby providing sufficient current to heat the filament of the light source 1 to a high degree of brilliancy, in an exceedingly short time.

105

The opening of the control relay 2 opens 115 the circuit 17, and the current from the terminals 13 takes a new course through the length of the resistor 12 and the primary coil 15 of transformer 9, returning to the complementary terminal 13. The current taken 120 by the transformer 9 to supply the light source 1 is so small that the drop in potential in the portion of the resistor 12 which parallels the valve 10 is less than the drop in potential through the valve 10, which is thus 125 automatically eliminated.

115

The two above-described adaptations of 130 my invention provide means for energizing the light source of oscillographs in such a relatively short period of time as to be negli-

130

gible so far as the detrimental effect of a time lag is concerned.

Oscillographs without a shutter or with the shutter open, and supplied with a photographic film, may be left connected to a commercial transmission line and will automatically record the current pulsations, when any short circuit sufficient to operate the control relay occurs. By this means, records may be had of the actual phenomena of a commercial circuit, without entailing the risk and expense incidental to an experimental short circuit which is required at the present time because the oscillograph of the prior art requires an appreciable time for the light source to heat up to full brilliancy.

My invention is not limited to the specific details illustrated as it may be variously modified without departing from the spirit and scope of the invention as set forth in the appended claims.

I claim as my invention:

1. The combination with an incandescent lamp, of means for momentarily increasing the voltage impressed thereon to a value above the voltage supply therefor; said means comprising a condenser, means for charging said condenser, and means for discharging said condenser through said lamp.

2. In combination, a filamentary element, means for discharging stored electric energy through said element, whereby the momentary flow of current therethrough is in excess of the normal operating current, and means for preventing the flow of current through said element from decreasing to a value below the normal operating current after said stored electric energy has been discharged.

3. In combination, an incandescent lamp having a filament, a condenser, means for charging said condenser, and means for simultaneously connecting said lamp filament across said condenser and across said charging means.

4. In combination, an incandescent lamp, a condenser, means for charging said condenser through a circuit including an impedance, and means for discharging said condenser through a second circuit including said lamp.

5. In combination, an incandescent lamp, a condenser, direct-current voltage source connected to said condenser through a resistance, and means for connecting said lamp across said condenser.

6. In combination, an incandescent lamp, a condenser, a direct-current voltage source connected to said condenser through a resistance, and means for connecting said lamp across said condenser in response to an electrical disturbance on a transmission line.

7. An electrical system comprising a power line, means for deflecting a beam of light in accordance with the electrical varia-

tions caused by an electrical transient on said power line, and means responsive to said transient only for impressing said beam of light upon a light-sensitive material.

8. An electrical system comprising a transmission line, means, including an incandescent lamp, for deflecting a beam of light in accordance with the electrical variations caused by an electrical disturbance on said transmission line, and means for lighting said lamp in response to said electrical disturbance.

9. In an electrical system, a transmission line, means, including an incandescent lamp, for deflecting a beam of light in accordance with the electrical variations caused by an electrical disturbance on said transmission line, means for discharging stored electrical energy through said lamp in response to said electrical disturbance, whereby the momentary flow of current through said lamp is in excess of the normal operating current, and means for preventing the flow of current through said lamp for decreasing to a value below the normal operating current after said stored electric energy has been discharged.

10. In an electrical system comprising a transmission line and an oscillograph lamp, the method which comprises discharging a quantity of stored electrical energy through said lamp in response to a disturbance on said line.

11. The method of operating an oscillograph including an incandescent lamp which comprises discharging a quantity of stored electrical energy through said lamp and immediately thereafter passing sufficient current through said lamp to maintain it in an incandescent condition.

12. An electrical system comprising a transmission line, means, including an incandescent lamp, for supplying a beam of light and for deflecting said beam of light in accordance with the electrical variations caused by an electrical disturbance on said transmission line, and means for lighting said lamp in response to, and for the duration of, said electrical disturbance.

13. A recording system comprising a light-sensitive surface, a mirror, a source of light for passing a beam of light to said mirror and thence to said surface, and means, including said mirror, for deflecting said beam of light in accordance with the variations of a quantity, as effected by the occurrence of a transient, a device controlling energization of said source of light, and means responsive to the occurrence of said transient for actuating said device.

14. The combination with an electrical power circuit, a deflecting system including a reflecting surface, and means for controlling said system in accordance with a characteristic of a quantity of said power circuit,

of a light-sensitive surface, means for directing a beam of light to said reflecting surface and thence to said light-sensitive surface, and means responsive to the occurrence of a chance transient on said power circuit for operating said second named means.

15. An electrical system comprising a transmission line, means, including an incandescent lamp, for deflecting a beam of light in accordance with the electrical variations caused by an electrical disturbance on said transmission line, and means for controlling the current flow through said lamp in response to said electrical disturbance.

16. In combination, an electrical-transmission line, a deflecting system, means for controlling said deflecting system in accordance with a characteristic of a quantity of said transmission line, means normally inactive for supplying a beam of energy and for directing said beam into coacting relation with said deflecting system, a surface sensitive to said beam of energy, and means for activating said second means in response to the occurrence of a disturbance on said transmission line.

In testimony whereof, I have hereunto subscribed my name this 2nd day of June, 1926.

JOSEPH W. LEGG.
